UNITED STATES PATENT OFFICE.

HECTOR Q. RACINE, OF ATLANTIC, MASSACHUSETTS, ASSIGNOR TO RAYMOND K. HOYT, OF ATLANTIC, MASSACHUSETTS.

DOOR-SECURING MEANS.

Application filed September 10, 1924. Serial No. 736,988.

To all whom it may concern:

Be it known that I, HECTOR Q. RACINE, a citizen of the United States, residing at Atlantic, in the county of Norfolk and State 5 of Massachusetts, have invented new and useful Improvements in Door-Securing Means, of which the following is a specification.

The object of my said invention is the 10 provision of an easily and quickly applied and manipulated device for holding a door against opening, and one which is so constructed that in case of fire or any other emergency the door may be expeditiously 15 and easily released for the opening thereof.

Other objects and practical advantages 20 of the invention will be fully understood from the following description and claims when the same are read in connection with the drawings, accompanying forming part 25 of this specification, in which:—

Figure 1 is a view showing my novel device with the parts positioned to preclude opening of the door from the outside.

Figure 2 is a side elevation of the preferred embodiment of my invention per se.

Figures 3 to 6 are views of parts comprised in my novel device.

Similar numerals of reference designate 30 corresponding parts in all of the views of the drawings.

I show in Figure 1 a swinging door 1 together with the side stile 2 of a door frame, the said stile 2 being recessed at 3 for the 35 reception of a lug or lateral projection 4 on a metallic bar 5 comprised in my improvement, the opposite edges of the said bar 5 being toothed as designated by 6.

In addition to the bar 5 my novel safety 40 or securing device comprises a slidable member 7 that is adapted to straddle the bar 5 as shown in Figures 1 and 2, a rotary, spirally ribbed member 8 mounted to rotate in a bifurcated portion 9 of the member 7 and 45 adapted to engage one set of teeth 8, and a lever member 10 pivoted at 11 in an upstanding bifurcated portion 12 of the member 7 and having a comparatively short forward arm 13 adapted in the position shown 50 in Figures 1 and 2 to engage the other set of teeth 6 and also having comparatively long arm or handle as best shown in Figure 2. The slidable member 7 is preferably 55 shaped as shown in Figures 1, 3 and 6 in order to bear against the face of the door 1

and also against the stile 2 as appears in Figure 1.

In the practical use of my novel device, the bar 5 is engaged with the recessed stile as appears in Figure 1 and the door 1 is moved to fully closed position. The slidable member 7 is then moved on the bar by turning of the member 8 until its portions at opposite sides of the bar abut against the door face and against the stile 60 2 as shown in Figure 1. Manifestly when the member 7 is adjusted by the rotation of the member 8 against the door and stile as stated, opening of the door from the outside will be effectively prevented. 65

It will also be understood that when it is desired to open the door from within under ordinary circumstances, the member 8 may be turned to move the slidable member 7 away from the door and door stile when the door may be quickly and easily opened. In the event of a fire or any other emergency requiring quick opening of the door it is simply necessary to swing the handle of the lever 10 into upright position when 70 the member 8 will be disengaged from the adjacent teeth of the bar 5, and the member 7 may be slipped rearwardly on the bar 5 by the direct application of the hand 75 to the member 7.

It will be apparent from the foregoing that notwithstanding the simplicity of my novel device and the facility with which it may be applied and manipulated, the device when properly applied may be depended upon to prevent the opening of the door until a person at the inner side of the door desires that the same be opened. 80

I have specifically described the preferred 85 construction of my improvement in order to impart an exact understanding of said construction. I do not desire, however, to be understood as confining myself to the disclosed preferred construction, my invention being defined by my appended claims within the scope of which modifications may be made without departure from my invention. 90

Having described my invention, what I 100 claim and desire to secure by Letters Patent, is:—

1. A door securing device comprising a toothed bar having a lateral projection, a member slidable on said bar and adapted to be positioned against the inner face of 110

a door, a rotary spirally ribbed member mounted in and connected to the slidable member to enable its ribs to work in the interdental spaces of the bar, and adjustable means on the slidable member at the opposite side of the bar to the rotary member and adapted in one position to maintain the rotary member in engagement with the teeth of the bar and in another position to permit of movement of the slidable member at right angles to the length of the bar and movement of the rotary member out of engagement with the teeth of the bar.

2. A door securing device comprising a toothed bar having a lateral projection, a member slidable on said bar and adapted to be positioned against the inner face of a door, a rotary spirally ribbed member mounted in and connected to the slidable member to enable its ribs to work in the in-

terdental spaces of the bar, and adjustable means on the slidable member at the opposite side of the bar to the rotary member and adapted in one position to maintain the rotary member in engagement with the teeth of the bar and in another position to permit of movement of the slidable member at right angles to the length of the bar and movement of the rotary member out of engagement with the teeth of the bar; the said means being in the form of a lever pivotally connected to the slidable member and having a short arm to engage the bar and also having a comparatively long arm or handle.

In testimony whereof I affix my signature.

HECTOR Q. RACINE.

Witness:

LELAND M. CHUTE.
